US0D1110526S

(12) **United States Design Patent** (10) **Patent No.:** **US D1,110,526 S**
(45) **Date of Patent:** **** Jan. 27, 2026**

(54) **COOLING THERAPY DEVICE**

(71) Applicant: **Nice Recovery Systems LLC**, Boulder, CO (US)

(72) Inventors: **Joel Meisinger**, Boulder, CO (US); **Michael Ross**, Boulder, CO (US); **Gerry Taylor**, Boulder, CO (US)

(73) Assignee: **Nice Recovery Systems LLC**, Boulder, CO (US)

(**) Term: **15 Years**

(21) Appl. No.: **29/957,328**

(22) Filed: **Aug. 13, 2024**

Related U.S. Application Data

(63) Continuation of application No. 18/221,237, filed on Jul. 12, 2023.

(51) **LOC (15) Cl.** **24-01**

(57) **CLAIM**

The ornamental design for a cooling therapy device, as shown and described.

DESCRIPTION

FIG. 1 is a front perspective view of a cooling therapy device;

FIG. 2 is a front elevation view thereof;

FIG. 3 is a rear elevation view thereof;

FIG. 4 is a right-side view thereof;

FIG. 5 is a left-side view thereof;

FIG. 6 is a top view thereof; and,

FIG. 7 is a bottom view thereof.

(Continued)

The broken lines shown in the drawings depict portions of the cooling therapy device that form no part of the claimed design.
